MATRIX MEMORY SYSTEM

Jean François Marchand, Eindhoven, Netherlands, assignor to North American Philips Company, Inc., New York, N.Y., a corporation of Delaware

Filed Oct. 9, 1958, Ser. No. 766,311

Claims priority, application Netherlands Oct. 17, 1957

6 Claims. (Cl. 340—174)

This invention relates to a matrix memory system comprising a plurality of memory elements each of which is made of magnetic material having a high remanence.

In known systems of this kind the memory elements are each magnetically coupled to one of a first group of conductors and to one of a second group of conductors, means being provided for changing the magnetic state of a certain memory element by variation of the electrical state of the group conductors coupled to this memory core. In these known systems a pulse is supplied simultaneously to both conductors coupled to this core so that the double pulse causes the core to change its remanence state; the cores which are coupled to only one current-carrying conductor must not be influenced by this current. It has, however, been found that in practice the last-mentioned cores may nevertheless be influenced to a certain degree thus interfering with the memory operation.

The present invention obviates this disadvantage. In the matrix memory system in accordance with the invention the undesirable reaction on the elements which are coupled to only one current-carrying conductor is prevented due to the fact that all the conductors are short-circuited in themselves with the exception of the two conductors which are coupled to the memory elements the magnetic state of which is to be changed.

The invention will now be described more fully with reference to the accompanying drawings, in which:

Fig. 1 shows a system in accordance with the invention, Fig. 2 shows a hysteresis loop of a magnetic material which can be used in this system, and

Fig. 3 shows a modified embodiment of a system in accordance with the invention.

Fig. 1 shows diagrammatically a number of memory elements K11, K12, K13 . . . K32, K33 made of a magnetic material having a rectangular hysteresis loop and arranged according to a matrix. All cores of one horizontal row are coupled to one horizontal conductor H1, H2 and H3 respectively, and all cores of one vertical column are coupled to one vertical conductor V1, V2 and V3, respectively. The ends of the conductors are connected to a frame GR of a material of high electrical conductivity, for example copper. Switching contacts CH1, CH2 and CH3 and CV1, CV2 and CV3, respectively, are connected in series with the conductors, these contacts being shown as mechanical contacts in the drawing but being designed as electronic contacts in practice. Normally the contacts are closed so that the conductors CH1, CH2, etc. are short-circuited in themselves through these contacts and the frame GR. The contacts may, for example, be transformers the primary windings of which are constituted by the conductors H1, H2 and so on, a secondary winding of each transformer being short-circuited, for example, through a transistor so that the internal impedances of the transistors are stepped down towards the conductors. The short-circuit can be eliminated by rendering the transistors non-conductive.

2

Fig. 2 shows an example of a hysteresis loop *a*, *b*, *c*, *d*, *e*, *f*, *g*, *h*, *i*, *a*, of a magnetic material which can be used in the cores K11, K12, and so on. Each core can be either in a state of positive magnetic remanence

5 *P* or in a state of negative remanence *N*, these states corresponding, for example, to the binary digits 1 and 0. In the known matrix memory arrangements there are no short-circuit contacts CH1, CH2, and so on. A certain core, for example K22, can be set to a certain remanence state, for example the state *P*, by applying a current pulse *J* to the horizontal conductor CH2 and to the vertical conductor CV2 simultaneously. Thus the double pulse 2*J* is applied to the core K22. If this core was in the state *N*, the branch *a*, *b*, *c*, *d*, *e*, *f*, of the hysteresis loop is traversed so that the core is set to the state *P*. The cores K21, K23, K12 and K32 have only the single pulse *J* applied to them in order that their magnetic states are not changed under the control of the single pulse *J*. This means that the saturation

10 region *a*—*b* of the magnetization curve must be comparatively large and more particularly that the current strength JK, which corresponds to the "knee" *b* of the magnetization curve, must exceed the pulse strength *J*. Consequently comparatively exacting requirements must be satisfied with respect to the shape of the hysteresis loop so that the material is comparatively expensive. The hysteresis loop shown in Fig. 2 does not satisfy this requirement, for in this loop the pulse strength *J* exceeds the current JK corresponding to the knee *b* in the hysteresis loop. It should be noted that in practice the "knees" *b* and *g* generally are less sharply bent than is shown in the drawing.

15 The cores K21, K23, K12 and K32, to which only the single pulse *J* is applied, will be driven only under the control of this pulse and with the shape shown of the hysteresis curve along the branch *a*—*b*—*c*—*j*; consequently, on termination of the pulse, these cores do not return to the zero state *N* but will be set to the state *j*. In other words, the zero state is disturbed and this is undesirable.

20 If similarly in the system shown in Fig. 1 the binary digit 1 is to be stored in the core K22, the switch contacts CH2 and CV2 are switched over to the work position so that the conductors H2 and V2 are connected to the pulse source JB. As a result the core K22, similarly to what has been described hereinbefore, under the control of the double pulse 2*J* traverses the branch *a*—*b*—*c*—*d*—*e*—*f* of the hysteresis loop and passes to state *P*. The cores K21, K23, K12 and K32 likewise have a current pulse *J* applied to them through the conductors H2 and V2. In the system shown in Fig. 1, however, the conductors H1, H3, V1 and V3 now are short-circuited in themselves through the contacts CH1, CH3, CV1 and CV3 and through the frame GR. If now a small variation of the magnetic induction *B* occurs in these cores, for example in the core K21, a reaction current JR is produced in the short-circuited conductor V1, this current having a direction such as to oppose the change in the magnetization, its strength with sufficiently low impedance of the short-circuit being about equal to the current *J*—JK so that the core K21 is not driven beyond the knee *b* of the magnetization curve shown in Fig. 2 and on termination of the pulse returns to the state *N*. Thus the zero state *N* is not disturbed. To the short-circuited conductor V1 there are coupled, in addition to the core K21, the cores K11 and K31. Since these cores are driven by the short-circuit currents in the conductors coupled to them into the saturation state *a*—*b* only, the presence of these cores causes only a very slight increase in the impedance of the short-circuit of the conductor V1. Experiments have shown that the number

of cores associated with one conductor can be high without any difficulty, for example may be 100 or more, provided that the spacings between the cores are not too large, for example $\frac{1}{2}$ cm. or less. An advantage of the system described as compared with the known systems consists in that with the use of the same magnetic material the strength of the applied pulses can be greater so that the speed at which the system can be operated can be higher than in the known systems. The abrupt changes of the magnetization states in a core have a certain inertia, the speed of these changes being proportional not to the strength of the pulse but to the pulse strength less a constant value corresponding to the coercive force. This means that the rate of change increases with the pulse strength not proportionally but at a higher rate.

Reading-out of the information from a certain core, for example K22, can take place similarly. In this event, the conductors H2 and V2 are connected to a source the polarity of which is opposite to that of the source used in storing. When the core K22 is in the state 1, this core will pass to the state 0 so that a reaction pulse can be taken from an auxiliary conductor coupled to all cores (not shown in the drawing). A change of the magnetic state of the cores K21, K23, K12 and K32 is in this event prevented by the occurrence of reaction currents in the remaining short-circuited conductors similarly to what occurs in the process of storing information.

In the system described, the information is stored or read out by simultaneously applying a pulse to both conductors coupled to a certain core. However, it has been found that alternatively the remanence state of a certain core, for example K22, can be changed to the opposite state by applying a pulse to only one of the conductors H2 and V2, for example to the conductor H2, and eliminating the short-circuit of the other conductor V2. Consequently the conductor V2 is not connected to a pulse source and the pulse source to be connected to the conductor H2 must have a strength which is double that used in the preceding case. Although now the strength of the current passing through the conductor H2 is sufficient to cause the cores K21 and K32 also to pass to another remanence state, this is prevented by the reaction current which is produced in the short-circuited conductors V1 and V3. This measure provides simplified switching since the control pulse need be supplied to one of the control conductors only, so that the pulses to be applied to the various conductors need not be synchronized, as is the case in the known systems.

Fig. 3 shows a modified embodiment of the system in accordance with the invention, in which control pulses no longer have to be applied to individual control conductors, as in the case in the known systems, but only to a single control point SB common to all cores. Here also the cores of one horizontal row are coupled to one horizontal conductor H1 . . . H4 respectively and the cores of one vertical column are coupled to one vertical conductor V1 . . . V4 respectively. Switching contacts in the form of transformers CH1 . . . CH4 and CV1 . . . CV4 respectively, the primary windings of which are constituted by the conductors H1 . . . H4 and V1 . . . V4 respectively, are connected in series with the conductors. The ends of the secondary windings are connected to the emitters and collectors of transistors, for example TH3 and TV4, as is shown for the transformers CH3 and CV4. A tapping on each secondary winding is earthed while the bases of the transistors are connected to a negative voltage supply through resistances, for example RH3 and RV4. Normally the two blocking layers of the transistors are conductive, a current flowing from the emitter to the base and from the collector to the base. The internal impedance of the transistors when conducting is comparatively low and of the order of magnitude of a few ohms. Because of the transformers CH1 . . . CH4, CV1 . . . CV4 these resistances are materially stepped down towards the conductors

H1 . . . H4 and V1 . . . V4 so that the impedance of the primary windings is very low and forms a short-circuit. Furthermore all cores are coupled to the control conductors SH and SV each of which is connected at one end to the control terminal SB and at the other to earth. The control conductors are threaded through the various cores so that the currents in these conductors act in support of each other magnetically in the various cores. The conductor SH extends in parts parallel to all horizontal conductors H1, H2, H3 and H4 and is arranged in closest proximity to these conductors so that there is strong magnetic coupling with those conductors; hence, when an alternating current flows in the conductors SH, there is induced in a short-circuited conductor H1 . . . H4 a current the direction of which is opposite to that of the current in the conductor SH, the current amplitudes being substantially equal. The conductor SV is arranged similarly so as to extend parallel to the vertical conductors V1 . . . V4 and tightly coupled therewith magnetically so that an alternating current in the conductor SV produces an opposite reaction current in each vertical conductor V1 . . . V4. If required, this effect can be further enhanced by coupling the control conductor to the short-circuit conductors by means of a separate transformer auxiliary coupling, for example by means of an auxiliary core of high-frequency magnetic material, such as the core HK shown in broken lines. If required, the conductors SV and SH can be connected in series. Thus, when the control terminal SB is connected to a pulse source, the currents in the control conductors SH and SV are substantially balanced by the currents of opposite direction in the short-circuit conductors, so that these currents cannot exert any magnetic action upon the memory cores.

Storing of information in a certain core, for example K34, is effected by applying a positive potential to terminals BH3 and BV4 so that the transistors TH3 and TV4 are cut off, the short-circuit of the conductors H3 and V4 thus being eliminated. A current pulse of suitable polarity which is applied through the control terminal SB to the conductors SH and SV, causes the core K34 to pass to the desired remanence state. The other cores are not influenced by this pulse since each of these cores remains coupled to at least one short-circuited conductor so that any change in the state of magnetization is counteracted by the reaction current in these short-circuited conductors. Reading-out the information from a certain core can be effected similarly by applying in the manner described a pulse of opposite polarity to this core so that a reaction pulse can be taken from a read-out conductor coupled to all cores (not shown). This method has a disadvantage in that, in the process of reading-out, the information is destroyed and, if required, must be stored again. However, the information can alternatively be read out by means of an alternating current the amplitude of which is so small that the remanence state of the core concerned is not changed. If, for example, the information from the core K34 must be read out, the short-circuit of the conductors H3 and V4 is eliminated by cutting-off the transistors TH3 and TV4 while at the same time an alternating current is supplied to the control conductors SH and SV through the terminal SB.

If the amplitude of this alternating current only slightly exceeds the value JK which corresponds to the knee *b* of the hysteresis loop of Fig. 2, the magnetization reversibly traverses a small hysteresis loop in the proximity of the instantaneous remanence state N or P, so that, when the alternating current is switched off, the core returns to this remanence state. Since the hysteresis loop is differently curved in the proximity of the two remanence points N and P, that is to say, downwards in the proximity of the remanence point P and upwards at the remanence point N, an asymmetrical reaction current is produced in a read-out conductor coupled to all cores (not shown).

If the core K34 is in the state N, the positive phase of this reaction current, for example, exceeds the negative phase while conversely, if the core K34 should be in the state P, the positive phase of the reaction current would be smaller than the negative phase. By comparing the two phases of the reaction currents the remanence state of the core can be ascertained. It has been found that the amplitude of the read-out alternating current at the terminal SB can advantageously be made much greater than the value IK provided that the frequency of this alternating current is made sufficiently high, for example higher than 1 mc./s., in which event the process remains reversible, the value of the reaction current, however, being greater than with a comparatively small value of the read-out alternating current.

What is claimed is:

1. A matrix memory system comprising a plurality of memory elements composed of magnetic material having a substantially rectangular hysteresis loop, first and second groups of conductors, each element being magnetically coupled to one conductor of the first group and one conductor of the second group, means for varying the electric state of the conductor of each group coupled to a desired element, and means for short-circuiting each of the remainder of the conductors of the matrix, whereby undesirable remanences in the remaining elements of the matrix are eliminated.
2. A memory system as claimed in claim 1, wherein each element is an annular magnetic core.
3. A memory system as claimed in claim 1, wherein said short-circuiting means comprises a highly conductive frame surrounding said matrix, both ends of each conductor being connected to said frame.
4. A matrix memory system as claimed in claim 1, wherein said varying means comprises at least one control conductor magnetically coupled to each memory element and also arranged in close magnetic coupling prox-

imity to all conductors of each group, whereby the current in the control conductor produces a reaction current in each short-circuited conductor thus cancelling the effect of the control current therein.

5. A matrix memory system comprising a plurality of annular magnetic memory cores composed of magnetic material having a substantially rectangular hysteresis loop, first and second groups of conductors, each core being magnetically coupled to one conductor of the first group and one conductor of the second group, means for applying a writing pulse to the conductor of each group coupled to a desired element, each pulse having a magnitude one-half of that necessary to change-over a core from one saturation condition to another, and means for short-circuiting each of the remainder of the conductors of the matrix, whereby undesirable remanences in the remaining cores of the matrix are eliminated.
6. A matrix memory system comprising a plurality of annular magnetic memory cores composed of magnetic material having a substantially rectangular hysteresis loop, first and second groups of conductors, each core being magnetically coupled to one conductor of the first group and one conductor of the second group, means for short-circuiting each of the conductors of the matrix, means for applying a writing pulse to a selected conductor of one group, means for eliminating the short-circuit of a selected conductor of the other group, the magnitude of said writing pulse being sufficient to change-over a core from one saturation condition to another, whereby undesirable remanences in all cores other than the core coupled to said selected conductors are eliminated.
